UNITED STATES PATENT OFFICE.

HERMAN A. J. RIECKERT, OF NEW YORK, N. Y.

HINGE FOR FOLDING BEDSTEADS.

SPECIFICATION forming part of Letters Patent No. 234,334, dated November 9, 1880.

Application filed May 26, 1880. (Model.)

To all whom it may concern:

Be it known that I, HERMAN A. J. RIECKERT, of the city, county, and State of New York, have invented a new and useful Improvement in Hinges for Folding Bedsteads, of which the following is a specification.

My invention relates to hinges for folding bedsteads wherein the bed is fitted for being turned or closed into a stand or cabinet.

10 The object of the invention is to furnish a hinge which will permit ready removal of the bed from the stand without the necessity of unscrewing the hinge; and my invention consists in a hinge having its leaves formed separate, one being made with the hinge-pin as part of the leaf, and the other leaf made with a semicircular recess for the pin, and with a curved guide that enters an aperture provided in the first-mentioned leaf, and serves to prevent side movement of the leaves upon each other, and permits separation of the leaves when the hinge is open.

My invention is shown in the accompanying drawings.

25 Figure 1 is a sectional side view, representing the hinge as applied to use in a closed position. Fig. 2 is a similar view, showing the hinge open. Fig. 3 is a face view of the hinge in an open position.

30 Similar letters of reference indicate corresponding parts.

A represents the front portion or base of the stand or cabinet to which the bedstead-frame B is hinged, so that the latter may be turned to the upright position shown in Fig. 1, or turned outwardly ninety degrees, as in Fig. 2, to bring the bed to a horizontal position.

The hinge (of which two will generally be used for each bed) consists of the leaves a b, that are formed with screw-holes to permit their rigid attachment to the base A and bed B.

The leaf a, attached to base A, is formed with a semicircular groove or recess, a', across

its outer end and on its outer surface, and is 45 also formed with a curved lug or finger, d, that extends over the top of the recess a'.

The leaf b, attached to bed B, has the hinge-pin c formed with or attached to it, and is formed with an aperture, b', for the finger d to 50 enter when the leaves are closed together.

The finger d is made of such length that it will extend within the aperture b' during the movement required for opening the bed, and thus form a guide that will prevent lateral 55 movement. The curve of the finger is such that sufficient space is left for inserting the hinge-pin c into the recess or removing it therefrom when the hinge is open. By this construction the bed B may be disconnected from 60 the base readily. It is only necessary to open or turn down the bed and raise the hinged end free from the base.

I am aware that hinges have been constructed with the pin in one piece with a leaf, 65 and provided with slots for the passage of curved projections on the other leaf; but the weight and strain are brought to bear directly upon the said projections or fingers, so that a bedstead could not be separated from the stand 70 except by unscrewing the hinges. On the other hand, my fingers serve merely as a guide to prevent a lateral movement of the upper on the lower leaf and a separation, except in a horizontal position, while the strain is upon 75 the pin and recess of the respective leaves.

What I claim as new and of my invention is—

A folding bedstead-hinge consisting of the base-leaf a, having semicircular groove a' and 80 curved finger d, and the bedstead-leaf b, provided with the aperture b' and pin c, as shown and described.

HERMAN A. J. RIECKERT.
